UNITED STATES PATENT OFFICE.

WILLIAM B. GUERNSEY, OF NORWICH, N. Y., ASSIGNOR, BY MESNE ASSIGNMENTS, TO THE TORREY AUTOMATIC BRAKE COMPANY, OF NEW YORK.

AUTOMATIC CAR-BRAKE.

SPECIFICATION forming part of Letters Patent No. 289,091, dated November 27, 1883.

Application filed October 20, 1881. (No model.)

To all whom it may concern:

Be it known that I, WILLIAM B. GUERNSEY, a citizen of the United States, residing at Norwich, in the county of Chenango and State of New York, have invented certain Improvements in Automatic Car-Brakes, of which the following is a specification.

The invention relates to double-acting brakes operated by the draw-bar and having a reversal governor actuated by brake-shoes, which latter have permissible arcs of movement corresponding to that of their respective wheels or axles, and causing the draw-bar to apply the braking pressure by reverse movement, whether the cars are moving forward or backward. Heretofore such devices have been mounted in horizontal position and operated through complex engagement devices and a system of brake-levers fulcrumed to the brake-beam or to the car-body in a rigid manner. In my invention I place the principal lever of the apparatus in a perpendicular position suspended below the car-body, and arrange the other parts of the mechanism to correspond thereto, whereby I secure a better mechanical arrangement for the entire apparatus, and I fulcrum the system of brake-levers to the staff of the ordinary hand-brake on the car, thus providing an adjustable fulcrum, by means of which my apparatus can be rendered inoperative, or be operated subject to a high tension; and by a slight movement of the actuating devices I have further improved the details of the engaging apparatus, by means of which, in addition to the positive engagement which other machines of a like nature have produced, I secure, before this positive engagement, a partial or tentative engagement, by means of which the apparatus is rendered automatically adjusting, and is made much more efficient.

In the accompanying drawings, Figure 1 is a sectional elevation of a car-truck, with my brake mechanism applied. Fig. 2 is a detailed elevation of the disengaging device on a larger scale. Fig. 3 is an end elevation of the operating parts. Figs. 4 to 9, inclusive, are detached views of details hereinafter described. Fig. 10 is a sectional elevation, on a smaller scale, illustrating the device by which a change in direction of wheel rotation is made to op-

erate the adjusting device to effect the desired disengagement of the apparatus.

In Fig. 1 the car is represented as in front of the observer with the apparatus attached at its left end. The apparatus is suspended from the bed of the car between the draw-bar bolt and the bolster. The draw-bar 1 is pivoted to a rocking arm or motor-lever, 34, Figs. 2, 3, and 4, which is keyed to a shaft, 38, (see Fig. 3,) mounted in the cheek-plates 2, and 6c having also keyed to it a double-crank arm, 35, Figs. 3 and 5, on which are pins 36 36, bearing on the head of a T-shaped lever, 37, Figs. 2, 3, and 6, which turns on an axis, 38, carried by the hanger 39, in line with the shaft 65 38, but disconnected therefrom, and is engaged by a latch, 21, Figs. 2 and 9, swinging on a pivot, 20, on the main or power lever 3, so as to determine the transmission of motion from the draw-bar to the hanger 39, from which it 7c is communicated to the main lever 3 by the connecting-link 40. 8 is the fulcrum of the reversing-lever 9, attached to the bolster of the car or truck and connected with the main lever by the tie 10, and with the brake-beam 75 lever 12 by the tie 11. The lower end of brake-beam lever 12 is connected by a tie, 13, to the other brake-beam lever 14, and the latter is connected with the hand-brake staff 16 by the 80 brake-rod and chain 15.

In operation when the chain of the brake-rod 15 is wound upon the staff of the hand-brake 16 the brake-beams will be drawn together, so that the shoes will be carried near to the car-wheels in position for any slight 85 movement of the main lever 3 to apply the brakes, while if the chain on the hand-brake staff 16 is entirely unwound any movement of the main lever 3 may be made without finding a fulcrum for the system of levers, and thereby the brake becomes inoperative. I do not confine myself to this particular arrangement of 90 brake-rods and connections between the levers, as the lines of communication may be run in different ways; or I may arrange my main lever 3 with such construction of the brake apparatus that it would move in the opposite direction from that which this drawing illustrates. In this latter case the reversing-lever 95 9 would be dispensed with.

In Fig. 2 the controlling devices are shown on a larger scale. The main lever 3 is fulcrumed at 22, Fig. 7, some distance below its upper end, and carries a latch, 21, swinging from a pivot, 20, at the upper end of said main lever. (In Figs. 1 and 2 the fulcrum of the main lever 3 is concealed by the latch 21.) Upon the latch 21 are specially-shaped engagement teeth and guards, to be more fully described hereinafter. On the outer face of this latch, at 26, is a pin, to which is attached a pitman, 23. The other end of this pitman, at 24, is connected to a crank-arm, 25, keyed to the shaft 32. As this shaft is turned the arm 25 swings from the position 24 to 27, Fig. 8, and thereby causes the latch 21 to be moved to the right and to resume its position upon the completion of the movement of the arm 25, for the purpose to be hereinafter explained. The arm 25 is caused to make its partial rotation between the positions 24 and 27 by the beams and shoes of the brake apparatus, as shown in Fig. 10, in which 28 and 29 are the brake-beams and shoes; 30, friction-rollers attached to the floor of the car; 31, a tie-chain or systems of tie-rods and bell-cranks connecting brake-beams 28 and 29, and in turn connected with the shaft 32, on which the arm 25 is fixed. The brake-beams are so suspended that they will move with the wheels when the shoes are pressed into contact through a limited arc of the wheel's revolution. As the shoes are carried in the direction of the wheel's rotation, when one beam moves vertically downward the other one rises vertically, and in doing so they shift the position of the tie-chains 31 longitudinally, rotating the shaft 32, and thereby moving the arm 25 with each change in direction of wheel rotation. Any application of the brakes prepares for this movement, the occurrence of which will depend upon the position of the brake levers and shoes. The amount of motion communicated to the shaft 32, as provided in the construction of the apparatus, is such as to move the arm 25 through its determined arc. As the movement of the draw-bar always precedes a change in direction of wheel rotation, the swinging catch 37 is brought into position with the engagement-tooth 33 on the latch 21, to be in readiness to move past the tooth 33 whenever the direction in wheel rotation is changed.

The draw-bar 1 is connected to the crank-arm 34, which is keyed to the shaft 38, Figs. 2, 3, 4, and as the draw-bar is extended or compressed the arm 34 has a rocking motion. This arm carries the rocking lever 35, on which are two pins, 36, Figs. 2, 3, 5, that work against the wings of the swinging catch 37, Figs. 2, 3, 6, and if this catch is free from engagement with the tooth 33 any movement of the rocking lever 35 communicates to it a swinging motion. The swinging catch 37 is pivoted in the axial line of the shaft 38, but free from it, being carried by the hanger 39, Figs. 2, 3, 7, with which hanger the shaft 38

has no connection. The hanger 39 is connected by the link 40 to the power-lever 3. When any movement of the draw-bar 1 finds the swinging catch 37 engaged with the devices of the latch 21, so that its swinging is arrested, the action of the pins 36 on the rocking arm 35 will move the swinging catch 37 longitudinally, forcing it to carry the hanger 39, and, through the link 40, move the power-lever 3 and apply the brakes. The movement of the power-lever 3, which applies the brake, is thus made dependent upon the engagement of the swinging catch 37 with the devices of the latch 21.

I will now describe the peculiar devices and construction of the latch 21. It is made with a deep broad groove, 41, extending longitudinally of the catch and in line with the arc, through which the bit 38^b of the swinging arm 37 may be caused to move. When the bit 38^b is moving through the portion 44 or 45 of the groove 41, the inner face of the projecting lug on the bit bears against the edge 42 of the groove, thereby preventing the latch swinging if any tension is put upon it, through a strain put upon shaft 26, by which the crank-arm 25 might be shifted between the positions 24 and 27. This prevents any shifting of the governing or adjusting device through extraneous causes at a time when it would disarrange the proper adjustment of the apparatus. As the bit 38^b approaches engagement with the tooth 33 it is brought in contact with the face 46 of the rib 43, thereby forcing the latch 21 to the right, causing a slight change in the vertical position of the brake-beams, the shoes being at that time away from the wheels and the beams hanging loosely, so as to be moved easily. The bit 38^b, having now engaged with tooth 33, may apply the brakes, but when a change of direction of draw-bar movement causes the bit to return upon its path it will be in the line of engagement with a tentative tooth, 47, which, but for the inclined face 46, it would not do, and it thereby produces a tentative application of the brakes, under which they will change their position in conformity to the direction of wheel rotation, if they had not done so in any previous operation of the mechanism. If the brake-shoes are already in their proper position, the bit 38^b, having moved into contact with 33, applies the brakes. If the brake-beams are not in their proper corresponding position, the movement of the 120 brake-beams changes the position of the arm 25, draws the latch and the tooth 33 to the right, during which movement the bit 38^b escapes past 33, and no definite application of the brakes is made. If the bit 38^b is resting 125 near the tooth 33 when the movement of a car is commenced, and that movement be in such direction that the bit 38^b is carried away from the tooth 33, the inner edge of 38^b comes in contact at 47 with the inner rim of the groove 130 41, causing a tentative application of the brakes, by which they take an adjustment ap-

propriate to the movement of the car. The tentative teeth serve another purpose, to wit: that of forcing the completion of brake-beam vertical movement whenever the direction of wheel rotation is reversed in correspondence with a change of direction of draw-bar motion. As the bit 38^b passes latch-tooth 33 the brakes are released and have no further tendency to continue their vertical motion, while as yet they have accomplished but one-half of their assigned movement; but the immediately-subsequent engagement of the bit 38^b with tentative tooth 47, by forcing the brakes again into contact with the wheels, compels the completion of the vertical movement of the brake-beams. The purpose of these peculiar conformations of the latch and swinging arm is to effect an automatic adjustment of the apparatus, by which it will be in a position for effective work, whether the engine be attached to the right or left end of the car or train.

The apparatus is attached to the body of the car, and the draw-bar and wheels and axles have movements relatively different in the varying conditions of service. The purpose is to secure the control of these relative differences of movement to actuate the automatic adjustment of the apparatus. All applications of the brake to resist an existing movement of the car are made by compression of the draw-bar when the car is moving forward, and by an extension of the draw-bar when the car is moving backward; but in relation to the apparatus the rotation of the wheels with the backward movement of the car while the engine is attached to the left is the same as with a forward movement of the car when the engine is attached to the right, a reversal of relations that is met by the tentative application of the brakes under certain circumstances, one of which would be found if after the car with the engine at its left end had been backed to a position where the engine would be attached to its right end and move to the right.

In that particular case the last rotation of the wheels would have been to the right. The bit 38^b of the swinging arm 37 would be below the tooth 33. The first movement of the engine, when attached to the right, would be, by the extension of the draw-bar 1, to apply the brakes; but in that condition of relations an extension of the draw-bar is required to not operate the brakes, and a disengagement of 33 is effected by backing the engine attached at the right, when, with the renewal of its forward movement, the contact of the bit 38^b against the rib at 46 would effect a tentative application of the brake, under which the beams would shift, the arm 25 change its position, the latch 21 be drawn to the right, the bit 38^b escape past 33, and then leave the draw-bar free for extension without putting on the brakes. If the engine be attached at the left end of a car, with the bit 38^b above the tooth 33 and the left brake-beam depressed, the ac-

tion of the draw-bar 1 on the rocking arm 35 will be to swing the arm 37 through the upper part of its arc of movement. If, while the train is in movement, the engineer resists its movement by slowing or reversing his engine, the operation of the draw-bar 1, acting through the rocking arm 35 and the swinging arm 37, brings the bit 38^b into engagement with the tooth 33 and applies the brakes. If this application be continued until the movement of the car is arrested and the power of the engine be applied so as to move the car backward, the change in direction of wheel rotation will, as before described, cause the latch 21 to shift to the right, will disengage the bit 38^b, which is then free to move through the lower arc of its permitted movement, and the movement of the car backward is without any interference of the brakes. If, while this movement is in progress, the engineer reverses his engine or slows in the movement, so as to resist the momentum of the car, the action of the draw-bar 1 will, through the movements before described, cause the bit 38^b to come in engagement with the tooth 33, and thereby apply the brakes. If the movement of the car be fully arrested and the engine then pulls it to the left, the change in direction of wheel rotation again effects the disengagement of the bit 38^b, and the car is free to move, as before described.

I wish to call attention to the peculiar functions which the various parts of this apparatus perform. The adjusting device is in a position of engagement, except when the change of wheel rotation effects a temporary disengagement, and the position of the swinging arm 37 when in contact with the tooth 33 is one which corresponds to the position of rest 105 in the draw-bar, and is the point where the definite engagement of the brake is effected. At each side of this point of rest a tentative engagement of the brake may be effected, whereby the appropriate adjustment of the 110 engaging device can be effected for any condition of service which can arise.

I do not limit myself to the use of the ordinary brake beams and shoes to actuate the adjusting device of an automatic draw-bar-brake 115 apparatus, as I contemplate the use of an independent system of brake shoes and beams for this purpose; nor do I limit myself to the frictional contact of shoes with the wheels, as I contemplate the application of shoes, clasps, 120 bars, and pulleys to any part of the wheels or axles directly or indirectly.

Any novel features herein shown and described, and not specifically claimed, I reserve the right to claim in future applications. 125

Having thus described my invention, what I claim as new, and desire to secure by Letters Patent, is—

1. In an automatic draw-bar brake, a longitudinally-moving draw-bar, in combination 130 with a tripping mechanism consisting of a pivoted swinging catch actuated by said draw-

bar through the medium of a crank-shaft carrying a rocking arm pivoted to the rear end of said draw-bar, and a double-crank arm operating in contact with the swinging catch, 5 substantially as and for the purposes set forth.

2. In an automatic draw-bar-brake mechanism, a longitudinally-moving draw-bar, and a pivoted swinging catch actuated by means of the draw-bar, through mechanism substantially as described, in combination with a pivoted latch having a longitudinal groove, within which the free end of the swinging catch operates, and an engagement-tooth placed centrally in said groove, as and for the purposes 15 set forth.

3. In an automatic draw-bar-brake mechanism, a longitudinally-moving draw-bar, a pivoted swinging catch actuated by said draw-bar through mechanism substantially as described, and a pivoted latch having a longitudinal groove within which the free end of the catch works, and an engagement-tooth placed centrally within said groove, in combination with balanced brake-beams having 20 vertical movements, a crank-shaft rotated by the vertical movements of said beams through suitable connections, and carrying a crank-arm, and a pitman connected therewith at one extremity and connected with the pivoted latch 25 at its other extremity, substantially as and for the purposes set forth.

4. In an automatic draw-bar-brake mechanism, a longitudinally-moving draw-bar, a pivoted swinging catch actuated by the said draw- 30 bar through mechanism substantially as described, a pivoted latch having a longitudinal

groove for the reception of the free end of the catch, and an engagement-tooth placed centrally in said groove, and connections between the said latch and balanced brake-beams, by 40 means of which the vertical movements of such beams shall effect a lateral movement of the latch, in combination with a hand-brake staff connected with the brake-beams in such manner as to constitute the fulcrum for the brake- 45 actuating system.

5. In an automatic draw-bar-brake mechanism, a longitudinally-moving draw-bar, and a pivoted swinging catch actuated by means of said draw-bar, through mechanism substantially as described, and provided at its free 50 end with a bit, 38^b, in combination with a pivoted latch, with a groove, 41, and engagement-teeth 33 42 47, and rib 43, with oblique faces 46, said latch having pitman-connection with the arm of a crank-shaft operated by a system of vertically-moving balanced brake-beams, substantially as and for the purposes 55 set forth.

6. The hanger 39 and cheek-plates 22, in combination with the shaft 38, carrying rocking arm 34 and double-crank arm 35, with its pins 36 36, and the T-shaped catch 37, with its bit 38^b and pivot-bearing 38^a.

7. The latch 21, provided with groove 41, 60 teeth 42, and rib 43, with its faces 46, and the tooth 33.
